(57) **CLAIM**

The ornamental design for a shuttle for a conveyor system, as shown and described.

DESCRIPTION

FIG. 1 is a top left perspective view of a shuttle for a conveyor system showing our new design.

FIG. 2 is a bottom right perspective view thereof.

FIG. 3 is a front view thereof.

FIG. 4 is rear a view thereof.

FIG. 5 is a top view thereof.

FIG. 6 is a bottom view thereof.

FIG. 7 is a left view thereof.

FIG. 8 is a right view thereof.

FIG. 9 is a top left perspective view of a shuttle for a conveyor system showing our new design according to an embodiment.

FIG. 10 is a bottom right perspective view thereof.

FIG. 11 is a front view thereof.

FIG. 12 is rear a view thereof.

FIG. 13 is a top view thereof.

FIG. 14 is a bottom view thereof.

FIG. 15 is a left view thereof.

FIG. 16 is a right view thereof.

FIG. 17 is a top left perspective view of a shuttle for a conveyor system showing our new design according to an embodiment.

FIG. 18 is a bottom right perspective view thereof.

FIG. 19 is a front view thereof.

FIG. 20 is rear a view thereof.

FIG. 21 is a top view thereof.

FIG. 22 is a bottom view thereof.

FIG. 23 is a left view thereof; and,

FIG. 24 is a right view thereof.

The broken lines in the drawings are for the purpose of illustrating portions of the shuttle for a conveyor system, which form no part of the claimed design.

1 Claim, 24 Drawing Sheets
